UNITED STATES PATENT OFFICE.

JOSEPH F. HADDOCK, OF ST. LOUIS, MISSOURI.

RAILWAY-MARKER.

1,172,523.

Specification of Letters Patent. Patented Feb. 22, 1916.

Application filed February 19, 1915. Serial No. 9,385.

To all whom it may concern:

Be it known that I, JOSEPH F. HADDOCK, a citizen of the United States, residing in the city of St. Louis and State of Missouri, have invented new and useful Improvements in Railway-Markers, of which the following is a specification.

This invention relates to railway lanterns of the type commonly denominated "markers," and has for its general object to provide means whereby an ordinary oil lantern of this description may be electrically lighted.

The character of lantern to which my invention relates is adapted to show two colors of light, red and green; and is provided with four bull's-eyes, three of which are of green glass, and one of red.

In practice a marker is placed on each corner at the rear end of the last car to extend beyond the sides thereof; and is normally set to show a green light to the engineer, a red light at the rear, and a green light at either side. Each marker is also rotatably mounted so that it may be readily turned to display green lights at the front, rear and side when the train moves on to a siding.

My invention embodies means for permitting the lantern to be turned in the usual way, for the purpose indicated above, without breaking the electrical contact.

My invention also embodies means whereby the lantern may be either automatically lighted by the act of mounting it on the bracket of the car; or through the medium of a conductor leading from a lamp socket, or other electrical station, on the car, and having contact members for establishing electrical connection with the electric lamps mounted in the lantern.

The invention also embodies various novel constructions and combinations of parts, all of which will be clearly set forth in the detailed description of the following.

In the accompanying drawings.—Figure 1 is a view, partly in section and partly in elevation, of a marker constructed according to my invention; Fig. 2 is a horizontal sectional view taken on the line 2—2 of Fig. 1; Fig. 3 is a view in elevation of the lower portion of my improved marker and of a section of the corner post of a car,

illustrating the manner of mounting the marker on a bracket provided on said corner post to establish electrical connection with contact-members provided on said bracket; Fig. 4 is a horizontal sectional view taken substantially on the line 4—4 of Fig. 1, certain parts being broken away to better illustrate the construction; Fig. 5 is a sectional view taken on the line 5—5 of Fig. 3; Fig. 6 is a cross sectional view taken on the line 6—6 of Fig. 4; and Fig. 7 is a view in elevation on a reduced scale illustrating the marker mounted on a "dead" bracket, and in a detached view a conductor provided with contact-members for establishing electrical connection with the marker.

Referring now to these drawings, the numeral 8 indicates, generally, a marker which, except for my added improvements, is of the usual or any preferred construction, and comprises a casing 9 having mounted therein bull's-eyes 10, 11, 12 and 13, of which the bull's-eye 10 can be considered as being red. One of the bull's-eyes, say 13, is mounted on a movable section 14 which is movable to give access to the interior of the casing. Within the casing there is provided a false bottom 15 adapted to support an oil lamp 16. The bottom 15 is provided, around its periphery, with a hollow annular ridge 17 which provides a recess in the bottom for receiving the lamp 16. Mounted on the ridge 17 opposite the bull's-eyes 10, 11 and 12, respectively, and communicating with the annular space 18 provided by said ridge, are hollow posts 19, on the top of each of which is mounted an electric lamp 20. It will be understood, of course, that the top of the posts 19 are provided with sockets for removably receiving the lamps 20. The conductors 21 leading from such sockets are carried through the posts 19 and connected to two main conductors 22 located in the recesses 18. The conductors 22 are held in position in the recesses 18 by an insulating plate 23 secured in the casing of the lantern under the false bottom 15. The conductors 22 are also insulated, and at a convenient point are extended through openings provided in the wall of the ridge 18 and the casing 9, as indicated in Fig. 6, and have their bared end portions connected to bind-

ing screws 23 mounted, respectively, in the ends of contact-rails 24 which partly encircle the bottom portion of the marker.

The rails 24 are mounted on a strip of insulating material 25 by means of screws, rivets or the like, 26, and a similar strip of insulating material 27 is interposed between the strip 25 and the casing 9, and said strips of insulating material are secured to the casing 9, as by means of screws 28. An insulating stop-block 29 (Fig. 4) mounted on the end of the strip 25 by means of screws 30 abuts against the binding screws 23, and a similar insulating stop-block 31 secured by screws 32 abuts against the opposite ends of the contact-rails 24. The bottom of the marker is grooved to provide a seat for a ring 33, which ring carries a bracket-arm 34, having a head 35. The numeral 36 indicates a support mounted on the corner post 37 of the car, and provided with a locking-groove to receive the head 35 of the bracket-arm 34.

The parts just described are of the usual construction, and when the marker is mounted on the support 36 it may be freely turned in the ring 33.

In order to provide for automatically lighting the marker as it is placed in position on the support 36 I mount beneath the support 36 a bracket 38 on which is mounted an insulating plate 39.

The numeral 40 indicates contact-members having twin spring-tongues 41, said contact-members being secured near opposite ends of the plate 39 by means of screws 42 passing upward through said plate and screwing into the bottom of said contact-members. One screw of each contact-member acts as a binding-post to which is connected a conductor 43, 44, respectively, which in practice would pass through a small opening in the corner post and connect with the source of electricity carried by the train.

Mounted on opposite sides of the bracket-arm 34 are two insulating-blocks 45, on each of which is mounted a plate 46 provided with an integral knife-edge contact-member 47 projecting at right angles to the plate 46 and to the insulating-block 45, each of the plates 46 having an integral portion at its top indicated by 48, which extends parallel with the top of the insulating-block 45 and terminates in a spring contact-finger, one of said contact-fingers, indicated by 49, being bent upwardly to engage the under side of the upper contact-rail 24, and the other of said contact-fingers, indicated by 50, being bent downwardly to engage the top side of the lower contact-rail 24. The portions 48 of the plates 46 are connected and covered by a block of insulating material 51.

It will now be seen that when the marker, constructed as described, is lowered into position on the support 36 the contact-members

47 will enter between the twin tongues 41 to form electrical contact therewith, which thereby establishes connection through the contact-fingers 49, 50, and rails 24 with the respective conductors 22, and thus current 70 may pass from the conductors 43, 44, to the lamps 20. It will furthermore be seen that as the marker 8 is turned in the ring 33 the contact-fingers 49, 50, will maintain contact with the rails 24 so that the electrical connection with the lamps 20 will not be disturbed. 75

In the event that the support 36 on the corner post of the car is not connected with the source of electricity the construction 80 illustrated in Fig. 7 will be employed. This arrangement differs from the construction previously described only in the fact that no contact-members are provided in connection with the support 36. In such case I employ 85 an ordinary flexible conductor 52, the respective wires of which are electrically connected with twin tongue contact-members 53 mounted on an insulating-block 54 carried by a bridge-piece 55, around which the conductor 52 may be wound, or to which it may be suitably connected in any preferred way 90 to carry the contact device as a whole. The opposite end of the conductor 52 will carry a plug 56 of the usual description for insertion in a socket. When the marker is in position on the support 36 the contact-members 53 are inserted over the contact-members 47 from above, and thus establish the electrical connection with the lamps of the 100 marker as will be understood.

The oil lamp 16 is carried in the lantern so that if for any reason the source of electricity should fail, or the electrical contact should be broken, said oil lamp could be 105 at once lighted, and thus the danger of the train traveling without its tail lights be avoided.

Many advantages incident to the use of electric markers might be enumerated, but 110 as most of these will be apparent to those skilled in the art, such as those of greater security, by obviating the necessity of handling, or carrying oil, and of economy and cleanliness, I think it necessary in this connection to emphasize only the fact that the use of my electric marker will enable a much brighter and more penetrating light to be employed, which is of great advantage in the case of a heavy rain, snow, or fog. 115 120

I claim:

1. A device of the character described, comprising a lantern having a plurality of differently colored bull's-eyes adapted to be turned to given positions for the purpose of 125 signal or warning, electric lamps operatively supported in the lantern and having conductors electrically connected therewith and extending part way around the lantern, a bracket-member rotatably mounted upon the 130

5 lantern and provided with supporting means, and free electric contact-devices mounted on said bracket-member and in electrical and slidable engagement with said conductors.

10 2. A device of the character described, comprising a lantern having a plurality of differently colored bull's-eyes adapted to be turned to given positions for the purpose of signal or warning, contact-devices on the exterior of the lantern electrically connected with said lamps, a bracket-member rotatably mounted upon the lantern and provided with supporting means, and a plurality of insulated contact-members mounted on said bracket-member, one set of said contact-members being free and affording means of connection with a source of current supply when the lamp is supported in position on 15 the car, and the other having slidable engagement with the contact-devices of said lantern and electrical connection with said free contact-members.

20 3. A device of the character described, comprising a bracket-member having insulated contact-members mounted thereon and provided with supporting means, a railway lantern having a plurality of differently colored bull's-eyes adapted to be turned to given positions for the purpose of signal or 25 warning rotatably mounted in said bracket-member, and having electric lamps mounted therein, a pair of insulated contact-rails provided on the exterior of the lantern, conductors leading from said lamps to the respective contact-rails, and means slidably engaging said contact-rails and electrically connected with said contact-members.

30 4. A railway marker comprising a portable bracket-member having fixed insulated contact-members mounted thereon and provided with supporting means, a lantern rotatably mounted in said bracket-member having electrical lamps mounted therein and provided with differently colored bull's-eyes adapted to be turned to given positions for the purpose of signal or warning, conductors leading from said lamps to the exterior of the lantern, and contact-devices carried, respectively, by said lantern and said contact-members and having corresponding slidable engagement, the contact-devices carried by the lantern being insulated therefrom and from each other and electrically connected with respective conductors of said lamps, and the other contact devices being electrically connected with said contact-members.

35 5. A device of the character described, comprising a lantern having electric lamps mounted therein and provided with a plurality of differently colored bull's-eyes adapted to be turned to given positions for the purpose of signal or warning, a pair of insulated contact-rails mounted on the lan-

tern, conductors leading from said lamps to the exterior of the lantern and to said rails, a portable bracket-member rotatably supporting the lantern and provided with supporting means, insulated contact-members 70 mounted on said bracket-member, contact-arms extending from the contact-members and engaging the respective contact-rails, a support on the car for receiving the supporting means of said bracket-member 75 whereby to support the lantern on the car, and means on the car for forming electrical connection with said contact-members.

6. A device of the character described, comprising a railway oil lantern provided with differently colored bull's-eyes adapted to be turned to given positions for the purpose of signal or warning, electric lamps operatively supported in the lantern and having conductors electrically connected therewith, a portable bracket-member carried by and adapted to rotatably support said lantern, and having supporting means, and a plurality of insulated contact-members carried by said bracket-member, one set of said 80 contact-members being free, and affording means of connection with a source of current supply when the lamp is supported in position on the car, and the other set having electrical connection with said lamp 85 conductors.

7. A railway marker having electric lamps mounted therein, a pair of insulated contact-rails mounted on the marker, conductors leading from said lamps to the exterior of the marker and to said rails, a bracket-member adapted to rotatably support said marker, a pair of contact-members mounted on and projecting from opposite sides of said bracket-member and insulated 100 therefrom, contact-arms extending from the respective contact-members and engaging the respective contact-rails, a support mounted on a car for engaging said bracket-member, and a pair of insulated contact-devices mounted on the car adjacent to said support and connected with a source of electricity carried by the car and adapted to establish electrical engagement with said contact-members when said bracket-member is 105 placed in engagement with said support.

8. A railway marker having electric lamps mounted therein, a pair of insulated contact-rails mounted on the exterior of the marker, conductors leading from said lamps 120 and connected to the respective contact-rails, a bracket-member adapted to rotatably support said marker, a pair of contact-members extending from opposite sides of said bracket-member and insulated therefrom, contact-arms extending from the respective contact-members and slidably engaging the respective contact-rails, a support on a car for engaging said bracket-member, a pair of insulated twin tongue contact-devices 125 130

mounted on the car adjacent to said support and positioned when said bracket-member is placed in engagement with said support to receive and form electrical engagement with said contact-members, and electric conductors leading from said contact-devices to a source of electricity on the car.

Copies of this patent may be obtained for five cents each, by addressing the "Commissioner of Patents, Washington, D. C."

In testimony whereof, I have hereunto set my hand in presence of two subscribing witnesses.

JOSEPH F. HADDOCK.
